Fig. 3

Fig. 4

Fig. 5

Fig. 6

FIGURE 1 is a top isometric view of a safety razor head guard, showing my new design;

FIGURE 2 is a bottom isometric view of the end opposite to that shown in FIGURE 1;

FIGURE 3 is a top plan view of the guard;

FIGURE 4 is a bottom plan view of the guard;

FIGURE 5 is a side elevational view thereof; and

FIGURE 6 is an end elevational view thereof.

The fragmentary broken line showing of the razor in FIGURE 5 and the broken line showing of the razor in FIGURE 6 are for purposes of illustration only.

I claim:

The ornamental design for a safety razor head guard, substantially as shown and described.
